UNITED STATES PATENT OFFICE.

WALTER C. WORKMAN, OF LOUDONVILLE, OHIO.

SPLICE-BAR.

1,038,471.

Specification of Letters Patent. Patented Sept. 10, 1912.

Application filed March 30, 1912. Serial No. 687,464.

To all whom it may concern:

Be it known that I, WALTER C. WORKMAN, a citizen of the United States, residing at Loudonville, in the county of Ashland and State of Ohio, have invented certain new and useful Improvements in Splice-Bars, of which the following is a specification, reference being had therein to the accompanying drawing.

10 This invention relates to rail joints, and has particularly for its object the production of an efficient rail joint which is provided with a rail bond retaining portion which will so hold the rail bond as to prevent 15 the same from becoming injured or accidentally severed.

Another object of this invention is the production of an efficient bond connection or rail bond protector which will bite into 20 the web of the rail, and thereby form an efficient retaining means independently of the securing bolts used in connection therewith.

With these and other objects in view this invention consists of certain novel constructions, combinations, and arrangements of parts, as will be hereinafter fully described and claimed.

In the drawings: Figure 1 is a detail perspective view of a pair of rails connected 30 by means of the rail bond protector forming the subject-matter of the present application. Fig. 2 is a detail perspective of one of the protector bars or joint plates. Fig. 3 is a perspective view of one end of 35 the protector plate looking from the outside thereof. Fig. 4 is a transverse section through the protector plate and rail. Fig. 5 is an enlarged detail view of the protector plate and rail showing the biting action 40 which takes place upon the web for constituting an efficient pocket for the rail bond.

Referring to the drawings by numerals it will be seen that 1 designates the rails which are clamped together by means of the 45 clamping plates 2. Each of these clamping plates is provided with the elongated apertures 3 to allow the lineal expansion of the rails under ordinary circumstances, and each of these plates 2 is provided with a 50 web engaging portion 4, said web engaging portion being provided with a concave inner face 5 which will constitute a substantial spring action of the web engaging portion 4 as the same engages the web of the rail.

A pair of parallel biting ribs 6 are formed 55 near the top of the plate 4, and these biting ribs are sharpened so that the same will firmly bite into the web of the rail as the plates 2 are clamped firmly in engagement therewith. It should be understood that 60 these edges are hardened to a sufficient extent so as to act effectively upon the web and firmly bite therein. The ordinary rail bond is first placed within the pocket 7 formed between the biting edges 6 and it 65 will be seen that since the rail bond as indicated at 8 is firmly held in this pocket, there will be no chance of the bond becoming severed by wear of the plate upon the bond for the reason that there will be no 70 sharp edges or corners which will bite into or wear upon the rail bond. Since the edges 6 will firmly bite into the web of the rail, it will be seen that the web engaging portions 4 of the plates 2 will form an efficient 75 gripping means and will not have any lateral movement relative to the web.

The upper end of the web engaging portion 4 is so formed as to fit snugly under the tread of the rail, and thereby constituting 80 a seal as indicated at 9 in Fig. 5.

What is claimed is:—

A rail bond device of the class described comprising a web engaging portion having a wide longitudinally extending 85 groove portion upon its inner face and near the lower edge thereof, an auxiliary groove portion extending longitudinally of said web engaging portion, and near the upper edge thereof for constituting a rail bond 90 receiving pocket, the edges of said auxiliary groove being sharpened to form longitudinally extending biting ribs, the upper edge of said web engaging portion adapted to fit snugly under the tread of a rail for 95 forming a seal against the entrance of moisture into said bond retaining pocket, and said bond retaining pocket adapted to firmly hold the bond therein against wear or against severance thereof. 100

In testimony whereof I hereunto affix my signature in presence of two witnesses.

WALTER C. WORKMAN.
